PAIR OF SUNGLASSES OR THE LIKE

Atherton R. Mitchell, San Francisco, Calif., assignor to
Renaud International, Ltd., Fitchburg, Mass., a cor-
poration of Delaware

Filed Sept. 12, 1968, Ser. No. 13,511

Term of patent 14 years

Int. Cl. D16—08

U.S. Cl. D57—1

FIG. 1

FIG. 2

FIG. 3

FIG. 4

FIGURE 1 is a front elevational view of a pair of sunglasses in accordance with my invention.

FIGURE 2 is a plan view thereof.

FIGURE 3 is a side elevational view thereof and,

FIGURE 4 is a partial sectional view taken substantially on line 4-4 of FIG. 1, with the temple portion being fragmentarily shown for convenience of illustration.

I claim:

The ornamental design for a pair of sunglasses or the like, substantially as shown and described.
